REVERSIBLE BOAT HOIST LINKAGE

Everett A. Johnson, 15 S. Prospect Ave.,
Park Ridge, Ill. 60068

Filed Feb. 2, 1973, Ser. No. 320,558

Term of patent 14 years

Int. Cl. D12—05

U.S. Cl. D12—60

FIG. 1 is a face view of a reversible boat hoist linkage embodying my new design.

FIG. 2 is a rear view of the reversible boat hoist linkage shown in FIG. 1.

FIG. 3 is a top edge view of the reversible boat hoist linkage shown in FIG. 1 and FIG. 2.

FIG. 4 is a section taken at 4—4 in FIG. 1.

I claim:

The ornamental design for a reversible boat hoist linkage, as shown.
